UNITED STATES PATENT OFFICE.

HENRY L. SMITH, OF WATERBURY, CONNECTICUT, ASSIGNOR TO THE E. J. MANVILLE MACHINE COMPANY, OF WATERBURY, CONNECTICUT, A CORPORATION OF CONNECTICUT.

METAL-HEADING MACHINE.

Application filed April 30, 1921. Serial No. 465,824.

To all whom it may concern:

Be it known that I, HENRY L. SMITH, a citizen of the United States, residing at Waterbury, in the county of New Haven and State of Connecticut, have invented a new and useful Improvement in Metal-Heading Machines, of which the following is a specification.

This invention relates to mechanism which 10 is more particularly designed for forming the heads on the bolt sections of such shackles as are used extensively for connecting the springs with portions of the frame of automobiles and other vehicles.

15 The object of the invention is to provide a simple, rugged and accurately operating mechanism which is adapted to be used in conjunction with a double-blow open die metal heading machine of well known type 20 for forming such shackles.

The invention is illustrated in connection with a heading machine of the class shown in United States Patent to Campbell, No. 926,170, June 29, 1909. In such prior machines the stock is fed longitudinally through dies which are closed transversely and is subjected to the blows of two punches which are carried by a vertically movable slide that is mounted on a horizontally reciprocating gate. On one forward movement of the gate, the stock is acted upon by one punch, and on the next forward movement of the gate the stock is acted upon by the other punch. In the shackle-forming machine the blank is fed down from above extending transversely of the machine and laid horizontally between folding dies and a mandrel, the dies being opened to receive the blank. When the blank is in position 40 the dies are closed and by the tool brought forward by the first movement of the gate, are folded horizontally so as to bend the blank about the mandrel into U-shape. Then with the dies thus held and tightly gripping the limbs of the blank, the next reciprocation of the gate causes the second tool to strike the blank and straighten out the bend and form the flattened head of the shackle. After this the completed shackle is ejected 50 and then the dies are unfolded and opened to receive the next blank.

The novel features of this invention reside in the construction and arrangement of the feeding mechanism, the dies and the

punch. In the accompanying drawings Fig. 1 shows a plan of the shackle-forming mechanism and so much of a well known heading machine as is necessary to an understanding of the relation of the improvement to such machine. Fig. 2 shows a side elevation with parts in longitudinal section of the shackle mechanism and connected parts of the machine. Fig. 3 is an elevation looking toward the shackle-forming mechanism, the machine frame being in transverse section on the plane indicated by the dotted line 3—3 on Fig. 1. Fig. 4 shows a detail of parts of the blank-feed operating mechanisms. Fig. 5 is a horizontal section showing the dies in the positions occupied when a shackle has been completed and is being removed. Fig. 6 is a similar view showing the dies in the positions occupied when a blank has been fed into them and gripped. Fig. 7 shows the dies in the positions occupied after a blank has been bent to U-shape. Fig. 8 shows the dies in the positions occupied after the second punch has shaped the head of the shackle. Fig. 9 is an enlarged side elevation of the dies with parts of their supports broken away. Fig. 10 is a front elevation of the same. Fig. 11 is a horizontal section on the plane indicated by the dotted line 11—11 on Fig. 9. Fig. 12 shows a blank. Fig. 13 the blank bent to U-shape. Fig. 14 a completed shackle. Fig. 15 is a detail view showing the fingers that carry the blanks down to the dies.

The gate 1 is reciprocated horizontally in the frame 2 by mechanism common to double stroke heading machines for instance by such mechanism as is found in the machine illustrated in the patent above referred to. In front of this gate and carried thereby is the ordinary vertically-movable slide 3 that is moved up and down between the reciprocations of the gate by the usual mechanism. Secured to the vertical slide is a forked ram 4 and above this is a punch 5 (Figs. 1 and 2).

100 Mounted in the die pocket in the frame is a mandrel 6 that has a semi-circular groove 7 in each side face. This mandrel forms the central die member. Back of the mandrel is a perforated plate 8 that is capable of a little longitudinal movement transversely of the die pocket in the front face of the backing block 9 that is bolted in posi-

tion in the die pocket. The mandrel rests upon a bracket 10 that is secured to the front of the slide plate 8 (Figs. 5 and 9).

The dies 12 of which there are two with semi-circular grooves 13 in their sides, are secured to die holders 14 on the upper ends of arbors 15. The die holder arbors are rotarily mounted in a carrier block 16 and have at their lower ends intermeshing spiral gears 17. Engaging these gears are spiral gears 18 fastened on a shaft 19 that is mounted in bearings 20 at the lower end of the bracket 10 (Figs. 9, 10 and 11). This construction permits the grooved faces of the dies to be oscillated away from the central die or mandrel on the shaft as a pivot as illustrated by dotted lines on Fig. 9 and allows the dies to be rotated about or folded back against the mandrel on the axes of the arbors from the positions illustrated in Fig. 6 to those shown in Fig. 5. Springs 21 connected between pins 22 projected from the lower ends of the carrier 16 and pins 23 projected from the bracket 10 tend to keep the dies closed toward the mandrel and the rotation of the gears causes the dies to unfold from parallel relation along side of the mandrel into alinement in front of the end of the mandrel. The shaft 19 is loosely held by a bearing in a lug 24 projecting from the block 9 (Figs. 1 and 3) and has an arm 25 (Figs. 2, 3 and 11) that is connected by a knuckle 26 with an adjustable link 27 which is connected with one end of a lever 28 Fig. 2. The other end of the lever 28 engages and is oscillated by a cam 29 on the cam shaft 30 for rotating the gears and swinging the dies open. The cam 29 is cut so as to normally swing the dies around from the sides of the mandrel to the front. After the dies have been unfolded into alinement in front of the mandrel and can swing no further owing to the coming together of their ends, the gears lock the members and further movement downward of the arm 25 caused by the cam 29 swings the carrier block 16 and the die holders which it carries so as to open the dies away from the end of the mandrel. The dies are swung backward or folded around the mandrel from the positions shown in Fig. 6 to the sides of the central die or mandrel by the engagement with the backs of the dies of the forked ram 4 as shown in Fig. 7 when that tool is brought up by the forward movement of the gate and when the slide that carries the tools is in its raised position. The backs of the die holders 14 are provided with inclined grooves 31 which receive the rounded plates 32 at the ends of the forked ram 4 when that tool comes up and engages the parts for swinging the dies around the mandrel (Fig. 7).

In order to guide the forked ends of the

ram 4 and prevent them from spreading, wings 33 and 34 are arranged so as to engage the back edges of the fork when they are brought forward for swinging the dies around the mandrel. The wing 33 is secured to a plate 35 fixed to the inside of the frame on one side of the die pocket and the wing 34 is secured to the plate 36 that is movably held near the inner wall of the other side of the die pocket (Fig. 7). Normally lying on one side of the backing block 9 and movable horizontally along the plate 35 is a filling block 37. On the other side of the backing block and movable horizontally along the movable plate 36 is a filling block 38. These blocks are slidably held to the faces of the plates and are mortised so that they may be moved out along the plates over the wings 33 and 34 from beside the backing plate 9 to the sides of the die holders as the forked ram is withdrawn so as to hold the dies from swinging open or unfolding (Fig. 8). On the upper faces near the inner edges of the filling slides are rack teeth 39 (Fig. 1) and engaging with these teeth are segmental racks 40 mounted on the horizontal shaft 41 (Figs. 2 and 3). Fastened to one end of the shaft 41 is a lever 42 that by a link 43 is connected with a lever 44 (Fig. 3). This lever at the proper times moves the slides forward and back, being oscillated by a cam 45 on the cam shaft 30. A spring 46 is arranged to hold the end of the lever 44 against the cam (Fig. 2).

The blanks 47 which are sections of round rod of the correct length with their ends properly threaded are fed from a hopper 48 down an inclined track (Fig. 2). The blanks are allowed to feed one at a time by the lifting of the cutoff gate 50 into the groove in the holder 51 on the slide 52 that is movable in ways in a bracket 53 fastened to the top of the machine frame. The cutoff gate is mounted on a vertically-movable slide 54 that is drawn down by a spring 55 and lifted by an angle lever 56 when the lever is engaged by a vertically-movable cam block 57 (Fig. 2). The slide 52 is connected with a lever 58 which is pivoted in the bracket 53 (Fig. 2) and which is connected by a link 59 with an angle lever 60 that is oscillated by a cam 61 on the cam shaft 30 (Fig. 4). A spring 62 pulls the link 59 so as to hold the lever against the cam (Figs. 2 and 4).

By this mechanism the slide carries the blank forward into the path of the vertically-movable spring fingers 63 which pick up the blank and carry it down and deposit it between the dies 12 and mandrel 7 (Fig. 2). The transfer fingers are attached to a slide 64 that is movable up and down guideways 65 fastened to the bracket 53. A screw 66 carried by the slide and engaging a lug

67 on the ways limits the downward movement of the finger slide (Fig. 2). The slide is connected by a link 68 with the end of a lever 69 fastened to one end of the shaft 70. 5 On the other end of the shaft is lever 71 which is connected by an adjustable link 72 with the end of a lever 73 (Fig. 2) which is oscillated by a cam 74 on the cam shaft (Fig. 4). A spring 75 holds the lever against the 10 cam. This mechanism causes the fingers to pick up a blank and carry it down and deposit it between the open dies and the mandrel, and the movement of the finger slide through the cam block 57 which it carries 15 causes the operation of the blank releasing gate.

When a blank is between the dies and the mandrel the dies are swung on the shaft 19 from the open position illustrated by the 20 dotted lines in Fig. 9 to the closed position shown by full lines in that figure so as to grip the blank between the dies and the mandrel and then with the blank in the position illustrated in Fig. 6, the fingers are drawn 25 up out of the way. Then the main tool-carrying gate is advanced with the forked ram in the plane of the dies so that the ends of the fork will engage and fold the dies back, the die holders rotating on the arbors 30 15. This movement of the dies bends the blank around the mandrel into the U-shape 76 as shown in Fig. 7. As the forked tool is withdrawn it is followed out by the blocks 37 and 38 which fill the spaces between the 35 die carriers and the side plates 35 and 36 as shown in Fig. 8. With the parts in these positions the movable side plate 36 is pushed over so as to pinch the dies together by the plungers 77 that are forced in by the well 40 known mechanism for closing the dies of the open die header which is fully set forth in the patent above referred to.

In the meantime the slide 3 has been drawn down and at the next forward movement of the main gate the punch 5 strikes a blow on the rounded end of the blank held in the dies and forms the head 78 and completes the shackle as illustrated in Fig. 8. As the gate retracts to draw back the punch the side 45 pressure on the dies is released and the completed shackle is pushed out by the rods 79 as shown in Fig. 5. The filling blocks are then withdrawn and the dies unfolded and swung open to be in position to receive the 55 following blank. The ejecting rods are attached to a plunger 80 (Fig. 5) which is reciprocated by the lever 81. A rod 82 connects the lever 81 with a fork 83 that is engaged and reciprocated by a cam 84 on the 60 cam shaft (Fig. 2). In order that the threaded ends of the shackle shall not be battered against the ends of the ejecting rods, the plunger 80 is held up by one end of a lever 85, the other end of which has an adjusting screw 86 that engages with a boss 87

on a disk 88 that is forced forward by buffer springs 89 (Figs. 1 and 2).

The invention claimed is:—

1. A metal heading machine having a mandrel, dies adapted to be folded around the mandrel for bending and holding a blank, a reciprocatory tool for engaging and folding the dies, and a reciprocatory tool for shaping the bent blank held by the folded dies. 75

2. A metal heading machine having a mandrel, dies adapted to be folded around the mandrel for bending and holding a blank, a reciprocatory tool movable in one plane, for engaging and folding the dies, and a reciprocatory tool movable in the same plane, for shaping the bent blank held by the folded dies. 80

3. A metal heading machine having a mandrel, dies adapted to be folded around the mandrel for bending and holding a blank, and a horizontal reciprocating gate carrying a tool for engaging and folding the dies also carrying a tool for shaping the bent blank held by the folded dies. 85

4. A metal heading machine having a mandrel, dies adapted to be folded around the mandrel for bending and holding a blank, a horizontally reciprocating gate, a vertically reciprocating slide carried by the 95 gate, a tool for engaging and folding the dies, and a tool for shaping the bent blank held by the folded dies, said tools being mounted in said slide. 90

5. A metal heading machine having a 100 mandrel, dies adapted to be folded around the mandrel for bending and holding a blank, a reciprocatory tool for engaging and folding the dies, reciprocatory blocks for engaging and holding the dies folded, and a reciprocatory tool for shaping the bent back blank held by the folded dies. 105

6. A metal heading machine having a mandrel, dies adapted to be swung from and toward the mandrel for receiving a blank 110 and folded around the mandrel for bending the blank, a reciprocatory tool for engaging and folding the dies, and a reciprocatory tool for shaping the bent blank held by the folded dies. 115

7. A metal heading machine having a mandrel, oscillatory and rotatory dies adapted to cooperate with the mandrel for bending a blank, means for oscillating the dies from and toward the mandrel, and means for rotating the dies around the mandrel. 120

8. A metal heading machine having a mandrel, dies adapted to be swung from and toward the mandrel for receiving a blank, and folded around the mandrel for bending the blank, a reciprocatory tool for engaging and folding the dies, reciprocatory blocks for engaging and holding the dies folded, and a reciprocatory tool for shaping the bent blank held by the folded dies. 125

9. A metal heading machine having a mandrel, dies adapted to be swung from and toward the mandrel for receiving a blank, and folded around the mandrel for bending the blank, a reciprocatory tool for engaging and folding the dies, mechanism for first unfolding the dies and then swinging the dies from the mandrel, and a reciprocatory tool for shaping the bent blank held by the folded dies. 70
10. A metal heading machine having a mandrel, dies adapted to be swung from and toward the mandrel for receiving a blank, and folded around the mandrel for bending the blank, a forked tool for engaging the backs of and folding the dies about the mandrel, and a reciprocatory tool for shaping the bent blank held by the folded dies. 75
11. A metal heading machine having a mandrel, dies adapted to be folded around the mandrel for bending and holding a blank, a reciprocatory tool for engaging and folding the dies, reciprocatory blocks for engaging and holding the dies folded, means for forcing the dies and mandrel together transversely between said blocks, and a reciprocatory tool for shaping the bent blank held by the folded dies. 80
12. A metal heading machine having a mandrel, oscillatory and rotary dies adapted to be swung and folded around the mandrel for bending and holding a blank, a reciprocatory tool for engaging and folding the dies, reciprocatory blocks for engaging and holding the dies folded, means for forcing the dies and mandrel together transversely between said blocks, and a reciprocatory tool for shaping the bent blank held by the folded dies. 85
13. A metal heading machine having a mandrel, rotary dies adapted to cooperate with the mandrel for bending a blank, means for rotating the dies around the mandrel, and a transversely movable slide carrying said mandrel and the dies. 90
14. A metal heading machine having a mandrel, oscillatory and rotary dies adapted to cooperate with the mandrel for bending a blank, means for oscillating the dies toward and from the mandrel, means for rotating the dies around the mandrel, and a transversely movable slide carrying said mandrel and the dies. 95
15. A metal heading machine having a mandrel, dies adapted to be folded around the mandrel for bending and holding a blank, a reciprocatory tool for engaging and folding the dies, reciprocatory blocks for engaging and holding the dies folded, a transversely movable slide carrying said mandrel and dies, mechanism for moving said slide transversely, and a reciprocatory tool for shaping the bent blank held by the folded dies. 100
16. A metal heading machine having a mandrel, dies adapted to be folded around the mandrel for bending and holding a blank, a reciprocatory tool for engaging and holding the dies, reciprocatory blocks for engaging and holding the dies folded, a transversely movable slide carrying said mandrel and dies, mechanism for moving one of said blocks transversely against the dies, and a reciprocatory tool for shaping the bent blank held by the folded dies. 105
17. A metal heading machine having a mandrel, oscillatory and rotatory dies adapted to cooperate with the mandrel for bending and holding a blank, and means for oscillating and rotating the dies. 110
18. A metal heading machine having a mandrel, dies adapted to cooperate with the mandrel for bending and holding a blank, rotatory die holders, and an oscillatory carrier supporting said rotatory die holders. 115
19. A metal heading machine having a mandrel, dies adapted to be folded around the mandrel for bending and holding a blank, a reciprocatory tool for engaging and folding the dies, a reciprocatory tool for shaping the bent blank held by the folded dies, and means for ejecting the shaped block from the dies before the dies are unfolded. 120
20. A metal heading machine having a mandrel, dies adapted to be folded around the mandrel for bending and holding a blank, a reciprocatory tool for engaging and folding the dies, means for squeezing the dies together transversely, a reciprocatory tool for shaping the bent blank held by the folded dies, and means for ejecting the shaped blank from the dies before the dies are unfolded. 125
21. A metal heading machine having a mandrel, dies adapted to be opened from the mandrel and folded around the mandrel, means for feeding a blank between the mandrel and dies when the dies are unfolded, means for folding the dies around the mandrel and bending the blank, and means for ejecting the bent blank before the dies are unfolded. 130
22. A metal heading machine having a mandrel, dies adapted to be folded around the mandrel, means for feeding a blank between the mandrel and dies when the dies are unfolded, means for folding the dies around the mandrel and bending the blank, and means for ejecting the bent back blank before the dies are unfolded. 135
23. A metal heading machine having a mandrel, dies adapted to be folded around the mandrel, means for feeding a blank between the mandrel and dies when the dies are unfolded, means for folding the dies around the mandrel and bending the blank, and means for ejecting the bent blank from the dies. 140
